UNITED STATES PATENT OFFICE.

CHARLES E. WHITE, OF MOLINE, ILLINOIS, ASSIGNOR TO DEERE & MANSUR COMPANY,
A CORPORATION OF ILLINOIS.

DISK MARKER FOR CORN-PLANTERS.

1,215,599.

Specification of Letters Patent. Patented Feb. 13, 1917.

Application filed May 16, 1910, Serial No. 561,594. Renewed June 9, 1916. Serial No. 102,799.

To all whom it may concern:

Be it known that I, CHARLES E. WHITE, a citizen of the United States, residing at Moline, in the county of Rock Island and

5 State of Illinois, have invented certain new and useful Improvements in Disk Markers for Corn-Planters, of which the following is a specification, reference being had therein to the accompanying drawing.

10 This invention relates to improvements in the devices which are used in connection with planters for the purpose of marking the lines on the ground, which are successively followed as guides for the planter 15 as it moves first in one direction and then in the other across the field.

The principal object of the invention is to provide a marker mechanism of few parts and one adapted to be cheaply and quickly 20 made and assembled. In a marker constructed in accordance with my invention it is possible for the parts to vary considerably in relative sizes without detriment.

Figure 1 is a plan view of the rear part 25 of the planter mechanism and of a marker embodying my improvements.

Fig. 2 is a rear elevation of the same.

Fig. 3 is a longitudinal section of the marker.

30 Fig. 4 is a face view of the disk and its bearing clip.

Fig. 5 is a perspective of the journal part in which the pole or rod is adjustably secured.

35 In a marker constructed in accordance with my invention, a hollow journal or bearing part with an axial aperture rectangular in cross section is fitted upon a square pole, preferably made of wood. The bear-

40 ing piece is provided with a flange arranged diagonal to the axis of the pole; and upon this piece the disk is journaled, the concave side of the disk contacting with the outer face of the flange and the disk being 45 held against axial displacement by means of a single retaining clip riveted to the disk, which bears against the inner face of the bearing flange.

The marker pole 1 is hinged on a horizontal longitudinal axis to the rear end of 50 the planter frame 2 and can be adjusted

in a position to the left of the plane as shown in Fig. 1, or can be swung from that position about its pivotal connection 3 to the right of the planter. The planter is 55 shown in the drawings with the usual covering wheels 4, 4, axle 5, seat 6, etc.

The pole 1 is rectangular in cross section. The journal piece 8 is formed with the bearing ring 9 having a central rectangular aperture 10 and the securing plate or arm 11 adapted to lie flat against one of the sides of the pole and formed with the bolt hole 12 registering with the bolt hole 13 in the pole. The eye-bolt 14 engages these bolt 60 holes and secures the bearing piece 8 against both rotation and axial movement with respect to the pole. It is formed with the eye 15 at its forward end, to which is attached the rear end of the guy rope or wire 16, the 70 front of which is attached to the frame parts of the planter. This guy serves to hold the disk to its work and prevent it from being swung in horizontal planes backward about the vertical pivot 17 of the 75 universal connection between the pole 1 and the frame 2.

The ring or flange part 9 of the bearing piece 8 is formed integral with the arm 11 and lies in a plane making an acute angle 80 rather than a right angle with this securing arm 11. The arm is provided with the two longitudinal ribs 18, which are adapted to embrace the two faces respectively of the pole 1, which are adjacent the front vertical face 19 of the pole against which the securing arm 11 is held. These ribs 18 assist in holding the bearing piece securely 85 in position upon the pole.

The disk 20 is mounted with its convex 90 side facing away from the planter and is provided with the central aperture 21 of a sufficient size to permit the disk to surround the pole 1, but still of a diameter smaller than that of the ring or flange part 9 of 95 the bearing casting 8. The annular clip 22 is riveted to the concave face of the disk and is formed to fit snugly over the peripheral edge of the ring 9 and to engage the inner face of the ring. The disk is thereby journaled about the axis of the pole as a center 100 and is free to rotate upon the ring 9, being

retained against axial displacement in one direction by the parts of the disk immediately surrounding the central aperture 21 and in the other direction by the clip 22.

- 5 By mounting the disk, as has been described, it is disposed at a considerable angle to the line of advance, which causes the disk to cut a wide mark or furrow, which can easily be seen from a considerable distance. This inclination of the disk is provided for by a simple and economical arrangement of one or two cheaply made parts, which hold the disk securely in position while permitting it to freely rotate.
- 10 15 By providing other bolt holes, such as 13', the marker can be adjusted for different desired distances between the rows of plants.

It will be observed that with the construction which I have described it is possible for 20 the size of the pole to vary considerably with respect to the journal piece. It is well known that in the cheap production of wooden elements, such as these poles, there is relatively wide variation in size between 25 one element and another, and it is also well known that in the cheap production of castings, such as the journal pieces 8, there will be considerable variation in size between one casting and another. If it were attempted to so form the castings as to have them accurately fit the poles on all sides, obviously in many cases the castings would be loose on the poles and in many other cases the castings would be too small to receive the poles. In accordance with my invention, however, the casting is designed with a considerable clearance so that there will be no difficulties whatever in assembling, and to prevent any looseness or play after 30 assembling, a bolt is provided for securely holding and clamping the single flat face of the arm of the casting firmly against the corresponding flat face of the pole.

In order to firmly reinforce the castings 45 and prevent breakage, the flanges or ribs 18 are provided which serve as braces between the arms and the rings. Preferably, though not necessarily, the bolt for securing the casting to the pole is provided with an eye and in this way the same bolt is made to serve not only as a securing means for the casting, but also as an attaching means for the guy rope or wire.

As heretofore remarked, the object is to 55 provide a disk marker which can be used with a light pole of wood. In case of breakage, the pole can be replaced by the user from material on the farm. The design of the marker parts is such that no nicety of fitting is required, it being merely necessary to provide the wooden piece with the apertures at proper distances from the longitudinal center of the machine to allow the marker to be set at different places, accord-

ing to the hill distances decided upon, say 65 distances of 36, 40 or 42 inches, from row to row. The pole can be more or less crudely fitted, provided it is arranged to slip through the disk. Even in case the disk sheet itself is broken or seriously impaired, 70 one can be temporarily provided from the nearest disk harrow. The central aperture in the disk does not depend upon the flange 9 of the adjustable holder. The pole passes directly through the small central aperture 75 of the disk. The flange 9 is on its outer surface convexed to conform to the face of the ordinary harrow disk eighteen or twenty inches in diameter. Neither at the shops nor on the farm is there any special labor 80 or machine work required to enlarge this aperture.

The ribs or flanges at 18, 18, also serve as holders or braces at the sides of the wooden pole and avoid the necessity of more 85 than one fastening device 14; and consequently, the farmer can quickly adjust the marker at any determined point along the pole. Even if this single fastener be passed through the aperture at 13', a short distance 90 from the end of the pole, the ribs 18, 18, and the vertical wall 8, serve to provide a firm bracing and fastening device.

It will be further seen that the pole is reversible from the left side to the right 95 side of the machine. It is straight from end to end, and the disk is held against being rotated around the pole axis and is always maintained, whether on the right or left, at the same working angle, both to the 100 axis of the pole and to the ground.

The box-like bracket 8, 18, 18, permits the use of pole pieces of varying thicknesses or widths, nicety of fitting not being required, as above described.

105 What I claim is:

1. In a corn planting marking device, the combination of a concavo-convex disk with a reduced central aperture and when in operation permanently held in fixed angular relation to the ground, a non-rotatable, bodily reversible pole, straight from end to end, adjustable bodily through the central aperture of the disk, and a non-rotatable disk holder having at its outer end a radially flanged plate with a concave surface conforming and fitted to the concave surface of the disk, and an inwardly projecting bracket integral with the flange and open on one side and loosely engaging with the pole 120 on the other sides to prevent its rotating about the pole, and a single, detachable, adjustable fastening device positively holding the bracket and disk to the pole axially and angularly after the end part of the pole has 125 been adjusted bodily through the disk aperture.

2. In a disk marker for a corn planter,

the combination of a marker pole, a journal piece formed with a ring portion having a rectangular aperture to receive the pole, with an eccentrically located arm extending 5 from the ring along and in engagement with one side of the pole only, and with longitudinal ribs embracing the pole and serving as braces between the ring portion and the arm, means for securing the arm against

the pole, and a disk mounted on the ring for 10 rotation about an axis at an angle to the axis of the pole.

In testimony whereof I affix my signature, in presence of two witnesses.

CHARLES E. WHITE.
